UNITED STATES PATENT OFFICE.

PARRISH C. WEEKS, OF KANSAS CITY, KANSAS, ASSIGNOR TO LUCY L. AHLBORN, OF SAME PLACE.

WINDOW-SHADE FIXTURE.

SPECIFICATION forming part of Letters Patent No. 611,345, dated September 27, 1898.

Application filed December 27, 1897. Serial No. 663,693. (No model.)

To all whom it may concern:

Be it known that I, PARRISH C. WEEKS, a citizen of the United States, residing at Kansas City, in the county of Wyandotte and State 5 of Kansas, have invented a new and useful Window-Shade Fixture, of which the following is a specification.

This invention relates to improvements in that class of window-shade hangers which 10 provide for the vertical adjustment of the shade to any desired height on the window-casing, so that the shade may be lowered to admit light and air at the top of the window, while affording a screen to the lower part 15 thereof, or it may be raised to cover the whole or any part of the window.

The object of the present invention is to provide a window-curtain hanger which may be easily and quickly applied at a minimum 20 cost to an ordinary window-frame.

A further object of the invention is to provide an improved hanger which may be adjusted to curtains of different widths and which is so constructed as to guide the 25 adjusting-cord out of the way of the shade and the hanger, thus obviating the liability of the cord being caught in or tangled with the shade or its hanger and insuring proper adjustment of the hanger with the cord.

With these ends in view the invention consists of an extensible curtain-hanger comprising wire members slidably coupled together and each bent to form a guide-loop between its shank and a depending arm and 35 with an oblique loop which lies at the lower free extremity of said arm and is in vertical alinement with said guide-loop, one arm having a journal-eye at a point intermediate of its length and the other arm provided with 40 an oblong loop which lies in the same horizontal plane as said journal-eye, combined with a shade-roller mounted in the journal-eye and loop of the hanger above the oblique loops thereof, and a running-cord threaded 45 through the guide-loops and having its lower length carried and guided across the hanger below the shade, as will be hereinafter more fully described and claimed.

To enable others to understand my invention, I have illustrated the same in the ac-

companying drawings, forming a part of this specification, and in which—

Figure 1 is a front elevation of a window with my improved hanger applied thereto and showing the same with its shade in a 55 partly lowered condition. Fig. 2 is an enlarged detail perspective view of the improved hanger detached from the shade, the operating-cord, and the window. Fig. 3 is an elevation looking at the left-hand end of the 60 hanger, shown by Fig. 2. Fig. 4 is an enlarged detail view, partly in elevation and partly in section, of the cord-clamp applied to the facing of a window-frame.

Like numerals of reference denote like and 65 corresponding parts in each of the several figures of the drawings.

Referring now by numeral to the drawings, 1 indicates my improved hanger. For simplicity and cheapness in the manufacture of 70 the hanger I make it of spring-wire, and to render the hanger capable of use in connection with shades of different widths it is made in sections, which are connected slidably together in a manner to render the hanger ex- 75 tensible longitudinally.

As shown by Fig. 2, the hanger consists of two members or sections 2 3, each of which is bent from a single piece of wire. The wire forming each section of the hanger is bent to 80 produce a smooth straight elongated shank 4, a loop 5, and a shade-carrying arm 6. The loop 5 is formed on each section of the hanger at the point where the shank and the carrying-arm are joined together, and these loops 85 5 on the hanger provide the vertical guide-eyes, through which the operating-cord is adapted to pass.

One section of the hanger has its depending shade-carrying arm 6 provided with a round 90 eye 7, while the depending shade-carrying arm of the other section of the hanger has a vertical elongated loop 8 formed therein. The eye 7 and the loop 8 of the shade-carrying arms forming parts of the hanger lie in 95 substantially the same horizontal plane, and they are adapted to receive, respectively, the cylindrical trunnion at one end of a spring shade-roller and the polygonal tenon or end of the spindle which protrudes beyond the 100

other end of said shade-roller, whereby the shade-roller is supported in the arms of the hanger in a manner to rotate freely therein, and at the same time the shade is adapted to 5 be adjusted vertically with said hanger.

The straight shanks 4 of the hanger-sections are adapted to lie alongside or overlap each other, as represented by Fig. 2, and said shanks are slidably connected together by 10 means of the loops 9 10, one of which is formed on the inner extremity of each hanger-shank and is adapted to be bent around the shank of the other section of said hanger. The described construction connects the two sections 15 of the hanger together for longitudinal adjustment and enables the hanger to be readily adapted to curtains which may vary in width.

Under all adjustments of the hanger-sections the shade-carrying arms 6 thereof lie at 20 right angles to the shanks and parallel to each other, and thus said arms 6 are well adapted to receive the trunnions of the shade-roller to support the latter parallel to the extensible shank of the hanger. The depending shade-carrying arms of the hanger are provided at 25 their free ends with loops or eyes 11, which stand obliquely to the length of the arms 6, and these oblique loops provide eyes in the vertical plane of the eyes formed by the loops 30 5, whereby the shade-adjusting cord 12 is adapted to pass through the eyes 5 and 11.

I employ a single continuous adjusting-cord for the hanger and the shade. This adjusting-cord is used in connection with the screw-eyes 13 or their mechanical equivalents. The screw-eyes are suitably attached to the window-casing at the cap or head thereof, and one strand of this adjusting-cord is passed horizontally through said eyes, thence carried 35 down through the eyes 5 and 11 at one end of the hanger, thence carried horizontally across the window-frame below the shade-roller, thence extended through the eye 11 and upwardly through the eye 5, and, finally, it is 40 extended through one of the screw-eyes 13 and carried down alongside of the major length of the strand to be attached thereto at a suitable point, indicated at 14. This free end of the cord may be fastened to the major length 45 thereof by knotting or tying the same around said major length, as at 14, and it will thus be seen that I provide a single operating-cord which is doubled for a part of its length and loosely connected with the shade-roller to 50 play freely through the screw-eyes 13 and the several eyes or loops 5 11 of the hanger itself. It will also be understood that the horizontal strands of the single operating-cord are connected with the shade-hanger in a 55 manner to be entirely free from the roller and the shade thereon, and thus the operation of unwinding or coiling the roller does not at all interfere with the adjustment of the operating-cord by which the hanger and the shade 60 may be raised or lowered to the required positions.

The shade-hanger is fitted against the face

of the window-casing in a horizontal position, so as to have the loops or eyes of said hanger bear or ride against the face of the window-casing. The shade is readily adjusted to the hanger by springing the arms 6 slightly and for a sufficient distance to permit the trunnion and polygonal end of the shade-spindle to fit in the eyes or loops 7 8, respectively, of 70 said hanger, and the shade-roller is free to rotate in the usual manner within said hanger to permit the shade to be drawn down or to coil the shade upon itself. The adjusting-cord 12 may be released to allow the hanger 80 and shade to descend by gravity whenever it is desired to expose the upper part of the window for the admission of light and air above the shade and its hanger, but to wholly screen the window it is necessary to adjust the hanger 85 and shade to the upper part thereof, under which condition of service it is necessary to fasten the adjusting-cord securely in place.

I provide a novel form of clamp for holding the adjusting-cord, the hanger, and shade 90 against displacement, which clamp is illustrated more clearly by Fig. 4 of the drawings.

In making the clamp 15 I take a stout piece of wire and bend it to produce the coil 16 and the binding-arm 17. The coil extends substantially at right angles to the plane of the binding-arm, and through the opening provided by coiling the wire upon itself to produce the coiled eye 16 is passed an attaching-screw 18, which is fastened in the window-casing at a 100 suitable distance from the sill thereof. This attaching-screw may be adjusted to compress the coiled eye 16 more or less in order to vary the pressure of the binding-arm 17 against the window-casing and the adjusting-cord 12, and 105 said screw thus serves as a means for the attachment of the clamp to the window-casing and as a means for varying the pressure or tension of said clamp on the adjusting-cord.

To apply my improved window-shade fixture to a window, it is necessary to attach the screw-eyes 13 to the cap-rail or head of the window-casing and then pass the adjusting-cord through said screw-eyes. One strand of the adjusting-cord is now carried downwardly 110 through the eyes 5 and 11 on one side of the hanger, after which it is led horizontally across the face of the window-casing and passed upwardly through the guides or eyes 5 and 11 at the other end or side of the hanger, and 115 finally it is carried through one guide or eye 13 and attached at 14 to the major length of the adjusting-cord. The hanger, having been previously adjusted to accommodate 120 itself to the width of the window and the shade-roller, is now arranged in the bight or loop of the adjusting-cord to occupy a horizontal position and to ride against the sides of the window-casing, and the shade is now adjusted to the hanger by fitting its cylindrical trunnion 125 in the eye 7 and the polygonal end of its spindle in the loop 8. The adjusting-cord 12 may be engaged with the binding-arm 17 of the clamp to be held securely in place thereby, or 130

said cord may be free from the clamp to allow the shade and hanger to be adjusted to the desired elevation.

From the foregoing description it is evident that my improved fixture may be applied to any ordinary window-frame quickly and easily, as it is only necessary to attach the screw-eyes for the running-cord.

The described construction obviates the employment of brackets to be fastened to the window-casing, which, as is well known, often require considerable care and experience in attaching the brackets to irregularly formed or shaped window-casings. The improved device may be readily applied to such irregularly-formed casings with ease and despatch, because it only requires the attachment of screw-eyes into the casing.

It is evident that changes in the form and proportion of parts and in the details of construction may be made without departing from the spirit or sacrificing the advantages of the invention.

Having thus described the invention, what I claim as new, and desire to secure by Letters Patent, is—

An extensible curtain-hanger consisting of the wire members, 2, 3, slidably coupled together and each provided with a depending arm, 6, and bent to form a guide-loop, 5, between its shank and said depending arm and also provided with an oblique loop, 11, which lies at the lower free extremity of said arm and is in vertical alinement with the guide-loop, 5, one arm having the journal-eye, 7, at 30 a point intermediate of its length and the other arm provided with an oblong loop, 8, which lies in the same horizontal plane as the eye, 7, combined with a shade-roller mounted in the eye and loop, 7, 8, of the hanger above the 40 oblique loops, 11, thereof, and a running-cord threaded through the loops, 5, 11, and having its lower length carried and guided across the hanger below the shade, substantially as described.

In testimony that I claim the foregoing as my own I have hereto affixed my signature in the presence of two witnesses.

PARRISH C. WEEKS.
